CURTAIN FIXTURE

Joseph E. Gaudet, Boston, Mass.

Application June 23, 1939, Serial No. 280,753

3 Claims. (Cl. 156—22)

My invention relates to curtain fixtures of the type used for sash or drapery curtains, and particularly to fixtures of this kind that are vertically adjustable to a limited degree.

5 One object of my invention is to provide a fixture of this character which is vertically adjustable within a limited range, and which may be secured in adjusted position by rotating the curtain rod or support member.

10 A second object is to provide a fixture of this character that may be used either on the sash itself or attached to the window frame or casing.

15 A further object is to provide a fixture of this character that is inexpensive, efficient and operative with facility.

20 My invention consists of a telescopic tubular member, a pair of slotted brackets attachable to the sash or casing, and the novel means by which the tubular member may be secured in adjusted position by rotation of the member.

25 In the accompanying specification and claims and the drawing forming a part thereof, I have described and illustrated a preferred form of my invention but do not confine myself to the particular embodiment, as modifications may be made within the scope of the appended claims.

In the drawing,

Fig. 1 is a sectional elevation in which my invention is embodied.

30 Fig. 2 is an end section of the invention on line 2—2, Fig. 1.

Fig. 3 is a sectional fragmental plan.

35 Fig. 4 is a sectional modified fragmental plan showing bracket adapted to secure it to the window sash.

Figs. 5 and 6 show in fragmental views one method for connecting the telescopic element and the tapped elements.

Referring to the drawing,

40 10 is the lower sash of a window, 11 the upper, and the brackets 12 are secured to opposite stops of the frame, at 13.

The brackets are formed with a slot 14 and ribs 15, 16, forming a channel in which the head 45 17 of bolts 18, 19 are guided without rotating, the stems of the bolts projecting through respective slots. The support for the curtain is

formed with telescopic elements 20, 21 and engage plugs 22, 23 tapped respectively right and left to engage stems of the bolts 18, 19, correspondingly threaded. Preferably these plugs are in the form of a cylindrical nut, tapered at 22 5 for easy engagement with the particular element of the telescopic member, a stud 25 projecting normal to the axis. Each element of the telescopic member is slotted in its end as at 24, and as the plugs engage with the telescopic member, 10 the assembly is rotatable as a unit, and when engaged with the bolts 18, 19, the rotation of the telescopic member will tighten both bolts in the brackets, between the heads and the ends of the respective plugs. While this form is 15 preferable, I may secure the plugs permanently in respective ends of the telescopic element.

In Fig. 4 I have indicated the bracket as being attached to the window sash instead of to the stops, and in such case the bracket is formed 20 with one rib 16' somewhat widened and pierced for screws or nails. This type of bracket is also applicable to the window header for overdrapes.

Having thus described my invention, I claim:

1. A curtain fixture comprising in combination, a pair of channeled brackets slotted through their major faces, a pair of headed bolts slidable but non-rotatable in the respective brackets, and a telescopic tubular curtain supporting member having the ends thereof axially tapped 30 to engage the respective bolts and rotatable to clamp the bolts and support in adjusted position on the brackets.

2. In a curtain fixture of the character described in claim 1, the tapped elements and the 35 tubular elements of the curtain support being relatively slidable and rotatable in unison.

3. In a curtain support having a pair of slotted brackets and a telescopic curtain supporting member, the combination of bolts respectively threaded right and left, slidable and non rotatable in the respective brackets, and a pair of elements tapped to engage respective bolts, and adapted respectively to engage and rotate in unison with opposite ends of the telescopic member.

JOSEPH E. GAUDET.
